MOUNTING FOR PROPELLER SHAFTS

Walter R. Smittle, St. Louis, Mo.

Application March 12, 1934, Serial No. 715,103

5 Claims. (Cl. 308—36.2)

This invention pertains to a mounting for propeller shafts, particularly the shafts of power boats. Considerable difficulty has been experienced in maintaining the bearings of the propeller shafts of power boats, particularly the outboard bearing which supports the shaft just forward of the propeller. It has also been found difficult to provide a suitable packing for the shaft at the point where it comes through the hull 10 of the boat. It has been discovered that a considerable portion of these difficulties arises from the fact that the shaft often becomes misaligned and consequently lateral strains are put upon the bearings and packings so that excessive wear results. Of course, as soon as sufficient wear has resulted to admit water, the wear is accelerated, particularly in the case of boats used on rivers where the water carries sand in suspension.

One of the objects of this invention, therefore, 20 is to provide a shaft mounting, including bearings and packing devices, so arranged that the shaft may be perfectly aligned in order to avoid lateral strains and other tendencies to excessive wear.

25 It has also been discovered that although when the shaft is first installed in a new boat, it may be mounted in perfect alignment; when the boat is placed in the water there is often a tendency for the hull to warp on account of the change 30 in the supporting forces. Under these conditions, the propeller shaft often changes its alignment when the boat is placed in the water.

Another object of this invention, therefore, is to provide mounting devices whereby the alignment 35 of the shaft and the bearings and packings may be readjusted to correct alignment after the boat has been placed in the water.

Another object is to provide improved bearing 40 and packing means whereby a perfect seal may be established against the entrance of water and such a seal maintained.

Another object is to provide such means of simple construction which may be manufactured 45 without excessive cost and which may be rugged and durable in service.

Further objects will appear from the following description taken in connection with the accompanying drawings, in which—

Figure 1 is a fragmentary sectional view of part 50 of a boat hull, showing the installation of a propeller shaft in accordance with this invention;

Figure 2 is an enlarged vertical sectional view of the boat log shown in Figure 1;

Figure 3 is a plan view of Figure 2;

55 Figure 4 is an enlarged view, partly in section,

showing the construction of the outboard bearing;

Figures 5 and 6 are views showing a preferred arrangement of clearance holes for the fastening bolts for Figures 3 and 4; and

Figure 7 is a similar view for the parts of Figure 4.

Referring now to the drawings, 1 represents the bottom of the boat through which the propeller shaft 2 passes. This shaft carries a propeller 3 in the usual manner. Such a shaft is usually supported in two or more bearings. An outboard bearing 4 is secured to the boat hull on the outside thereof and just forward of the propeller 3. From this bearing the shaft 2 passes forwardly 10 through the hull to an inboard bearing 5. This latter bearing may be a separate guide bearing suitably supported within the hull, or, in the case of a small boat, it may be the engine bearing. In Figure 1, however, it is illustrated as a 20 separate guide bearing. Positioned between the bearings 4 and 5 at the point where the shaft 2 passes through the hull, is the so-called boat log 6, which carries a packing device indicated at 7, adapted to seal the shaft against the entrance of 25 water at this point.

In accordance with this invention both of the bearings 4 and 5 and also the packing device 7 are mounted so that the alignment of the shaft therein may be adjusted. Referring, first, to the bearing 5, this may be provided at one or both ends, or at an intermediate portion thereof, with an outstanding flange 8 adapted to be secured to a support 9 mounted in any suitable manner on the boat structure. Mounted between the flange 30 8 and the support 9 is an aligning member 10. The member 10 is arranged for adjustment so as to vary either the angular position of the shaft or its vertical height. Toward this end the element 10 is provided on one side with a 40 cylindrical face 11. The opposite face 12 is preferably flat, or at least of less curvature than the face 11. The aligning element is placed so that the axis of the cylinder, of which the face 11 forms a part, is horizontal. In Figure 1 the face 11 is shown as concave with respect to the element 10. It may, however, be convex and the same result may be obtained. The flange 8 of the bearing has a cylindrical face matching the face 11 and adapted for angular adjustment therein. 45

50 Suitable fastening devices, such as the bolts 13, are arranged for securing the flange 8 and the element 10 against the support 9. These bolts are preferably arranged to pass through clearance holes in one or more of the parts 8, 9, or 10 so as to 55

permit a sufficient amount of shift of these parts relative to each other to accommodate the required adjustment. Figures 5 and 6 show an arrangement of clearance holes in the parts 8 and 10, respectively. It will be noted that the part 8 has its holes elongated in a circumferential direction so as to allow shift of the bolts for angular movement on the cylindrical face. The part 10, on the other hand, has its holes elongated in a direction axial of the cylindrical face. This allows for any necessary sidewise shift which is always slight.

It will be noted that this arrangement provides for both angular and vertical adjustment. The bearing may rotate in the cylindrical face 11 to adjust its angular position and thereafter the element 10 may be shifted vertically on the support 9 so as to adjust the elevation of the shaft at this point.

20 The packing device 7 is similarly mounted. In this case the boat log 6 provides the support. The element 10 has in this case a convex cylindrical face, indicated at 14 and a relatively flat face 12. The base 15 of the packing device 7 has a face 25 matching the cylindrical face 14. In this case also, bolts 13, passing through suitable clearance holes, are provided to clamp the parts in adjusted position. Suitable gaskets 16 of rubber, or rubber-like material adapted to yield under pressure, 30 may be placed between the matching faces in this case, so as to provide an effective and permanent seal.

In the case of the outboard bearing 4, this is supported on a suitable strut or hanger 17. In this case the cylindrical face is placed at 18 at the upper end of the hanger where it is supported on the boat hull. The element 10 again provides a cylindrical face, matching the face 18, and a relatively flat face which may be arranged to engage the hull 1 of the boat. A metallic plate 19 is preferably provided on the inside of the hull, while screws 13 provide the securing devices for securing the parts in adjusted position. In this case the screws may be arranged to pass through clearance holes in the elements 10 and 19 and to be threaded into the hanger 17, as illustrated in Figure 4. In this case also, gaskets 16 provide a seal against the entrance of water.

The curvature of the face 18 may be given a radius R, having its center at some point on the axis of the shaft 2, such as the point C, preferably close to the propeller 3. The adjustment for angularity then takes place about the center C, so that the elevation of the propeller remains substantially undisturbed.

The outboard bearing 4 may be constructed entirely of bronze or other suitable bearing metal, in which case it may be simply bored to provide a bearing 20 for the shaft 2. In case, however, the device should be constructed of other metal, a suitable bearing sleeve or bushing may be inserted in the usual manner. The bearing surface 20 may be provided with oil grooves 21 for distributing lubricant, in a well known manner. A lubricant supply duct 22 is provided passing downwardly along the hanger 17 from its upper extremity. At its upper end, it communicates with a suitable conduit 23 which may be secured in the duct 22 by threads, brazing or other suitable manner. A pad or packing 24 is provided which may be a rubber sleeve surrounding the conduit and held in place by the plate 19. Clearance is provided around the sleeve 24 so that its position may be maintained throughout any adjustment 75 relative to the plate 10. This provides means

whereby lubricant may be supplied to this bearing from the inside of the boat so that it will not be necessary to take the boat out of the water in order to lubricate the outboard bearing.

The bearing 4 is supplied at both ends thereof with packing devices adapted to seal the same against the entrance of water. These devices and the packing device 7, previously mentioned, are of the same construction so that the following description will apply to both.

Screwed into the end of the bearing 4 is a bearing plate 25 having a radial bearing or sealing face 26. The plate 25 is provided with an inner shoulder 27 arranged to leave a space 28 between the plate 25 and the bearing 4 adapted to provide a reservoir for lubricant. These reservoirs at both ends of the bearing 4 communicate with the duct 22 by means of a longitudinal duct 29, so that the lubricant supplied by the duct 22 may also be supplied to the reservoir spaces 28. The face 26 is provided with an annular groove 30 which communicates, by means of one or more ducts 31, with the reservoir space 28. In this manner lubricant may be supplied continually to the sealing face 26 of the packing device. Arranged for sealing engagement with the face 26 is a packing element 32, having a radial face accurately ground to fit the face 26. This element is loose on the shaft 2 and formed with a bore 33. Mounted within the bore 33 is a flexible sealing washer 34 adapted to make sealing contact with the inner surface of the bore 33 and the outer surface of the shaft 2. A retaining collar 35 is secured to the shaft 2 by means of a set screw 36 or other suitable fastening. This collar has an axially extending tongue 37 slidably fitted in a notch 38 in the rim of the packing element 32. This provides a key whereby the element 32 is carried in rotation with the shaft 2 while being loose thereon, so that it may vary in its alignment slightly in order to maintain the sealing contact with the face 26. A spring 39 seated in a bore 40 in the collar 35 bears against a metallic washer 41, which in turn bears against the flexible sealing washer 34 so as to maintain the latter firmly seated against the shaft 2 and the packing element 32. This washer provides a seal, permanently seated, against the entrance of water between the element 32 and the shaft. The element 32 in turn makes sealing engagement at the face 26 with the stationary parts of the bearing so that the entrance of water is entirely prevented.

The seal maintained at the face 26 is rendered the more effective on account of the fact that the lubricant is continually supplied at this face. In a similar manner, the packing device 7 is supplied with lubricant from the grease cup 42.

It will be seen that this invention provides a mounting whereby a propeller shaft may be maintained in perfect alignment and a perfect seal maintained to prevent the entrance of water either into the boat or into the outboard bearing. The shaft may be aligned in a preliminary fashion upon its original installation while the boat is still on the supporting blocks before it is placed in the water. Upon placing the boat in the water, the fastenings 13 may be loosened sufficiently to permit the necessary shift of the parts. In this manner, the shaft is permitted to realign itself in response to any warping of the boat structure when placed in the water. The realignment in each case involves two movements, which, of course, may take place simultaneously. One of these is an angular movement on the cylindrical face of the aligning

element 10. Such angular movement must necessarily take place about a center, which is the center of the cylinder of which this cylindrical face forms a part. As this center may not coincide with the point about which the angular movement of the shaft as a whole takes place, a lateral shift in a vertical direction is necessary in addition to the angular shift. This lateral shift is provided for by a movement of the element 10 on the flat face 12. Accordingly, each of the devices 4, 5 and 7 may align itself not only angularly, but in a vertical direction, so that its alignment coincides with that of the shaft and no side strains are imposed thereon. It will also be noted that after the re-alignment has taken place and the parts have assumed their new adjustment, the fastening devices 13 may be screwed up tight and secured in the adjusted relation so established. In the case of the outboard bearing, it will be noted that this adjustment may be made from inside the boat.

It will also be noted that the outboard bearing provides for both an angular and a fore and aft adjustment, so that the bearing may be adjusted to the propeller in the position in which the latter is to be maintained. The bearing itself may be adjusted to accurate alignment with the shaft so that an accurate guide bearing is provided. This is maintained against the entrance of water by sealing devices at opposite ends and lubricating means are provided for supplying lubricant both to the bearing and to the packing devices in such a manner that the water seal is maintained and perfect lubrication for the bearing is provided. The lubricant may be supplied from the inside of the boat and, if necessary, pressure lubrication may be established.

While this installation has been described as a unitary device, it will be understood that individual features and subcombinations thereof may be useful by themselves without reference to other features or the complete combination. It will also be understood that any desired combination of these separate features may be used and that the employment of such individual features or subcombinations is contemplated by this invention and is within the scope of the appended claims. It is furthermore obvious that various changes may be made in details of construction, within the scope of the appended claims, without departing from the spirit of this invention. It is, therefore, understood that this invention is not to be limited to the specific construction shown and/or described.

Having thus described the invention what is claimed is:

1. A supporting bearing for a propeller shaft comprising an outboard bearing for said shaft, a supporting hanger for said bearing attachable to a boat and having a cylindrical face, an aligning element having a cylindrical face matching that of said hanger and having a flat face shiftably engageable with a support, and means operable from inside the boat for securing said parts in adjusted relation. 5

2. In combination with a shaft and a support therefor, a controlling device such as a bearing embracing the shaft, and an alining plate interposed between said device and said support having a curved surface of long radius whose center lies adjacent the shaft and a relatively flat surface extending transversely of the shaft engaging corresponding surfaces on said device and said support, said plate being shiftable along the curve of its surface transversely of said shaft relatively thereto to align the shaft. 15 20

3. In combination with a shaft and a support therefor, a controlling device such as a bearing embracing the shaft, and an alining plate interposed between said device and said support having a curved surface of long radius and a relatively flat surface engaging corresponding surfaces on said device and said support, said plate being shiftable transversely of said shaft relatively thereto to align the shaft, and means providing a yielding facing for said alining plate 30 35 compressible to provide sealing engagement therewith.

4. In combination with a shaft, an inboard bearing and an outboard bearing, a boatlog, a packing device for the shaft, and an alining plate interposed between said device and said boatlog having a curved surface of long radius and a relatively flat surface engaging corresponding surfaces of said device and said boatlog, said plate being shiftable along the curve of its surface transversely of said shaft relatively thereto to align the shaft. 40 45

5. In combination with a shaft and a support therefor, a controlling device such as a bearing embracing the shaft, and an alining member interposed between said device and said support having a curved surface of long radius and a relatively flat surface engaging corresponding surfaces on said device and said support, said member being shiftable transversely of said shaft relatively thereto to align the shaft, and means providing yielding engagement between said member and said device and said support so as to make sealing engagement therewith. 50 55
